LUPU WILLIAM BRENNER, OF DETROIT, MICHIGAN.

PUPPET-VALVE.

1,342,419.

Specification of Letters Patent.

Patented June 8, 1920.

Application filed February 8, 1918. Serial No. 216,093.

To all whom it may concern:

Be it known that I, LUPU WILLIAM BRENNER, a citizen of the United States, residing at Detroit, in the county of Wayne and State of Michigan, have invented certain new and useful Improvements in Puppet-Valves, of which the following is a specification.

My invention relates to improvements in explosive engines and particularly to puppet inlet and outlet valves therefor. While the valve construction forming the subject matter hereof is especially designed for use in hydro-carbon engines, it is applicable to other constructions and purposes and is therefore not limited to such association.

The object of the invention is to improve the structure as well as the mode of operation of such valves whereby they will not only be cheapened in construction, but will be more efficient in use, automatic in action, uniform in operation, and unlikely to get out of repair.

The valve construction herein described is designed to afford a perfect fitting, quiet operating and quick acting valve which will materially increase the efficiency of explosive engines, particularly those of the high speed type commonly employed in automobiles and airplanes.

By the herein described construction; the cost of manufacture is materially reduced and extreme accuracy of manufacture is dispensed with. The valve is enabled to wear itself into a perfect fit with the seat and automatically compensates for any unevenness of its bearing, thereby insuring smooth uniform action even after the valve stem and guide become worn. The valve is designed to automatically find its seat independent of the valve stem and guide. The tendency to warp is reduced to minimum, lubrication insured and carburation materially aided. The valve may further be made to afford an initial or preliminary relief prior to the opening of the main valved orifice.

With the above primary and other incidental objects in view as will more fully appear in the specification, the invention consists of the features of construction, the parts and combinations thereof and the mode of operation of their equivalents, as hereinafter described and set forth in the claims.

Referring to the drawings, in which is

shown the preferred form of embodiment, Figure 1 is a sectional elevation of the improved valve and valve stem associated with a usual form of intake chamber, valve seat 60 and guide. Fig. 2 is a sectional detail view showing the valve operated to afford an initial or preliminary release of pressure. Fig. 3 is a top plan view of the valve head.

Like parts are indicated by similar characters of reference throughout the several views.

In Fig. 1 of the accompanying drawing, 1 is the high pressure chamber having the valved orifice 2, the periphery or rim of 70 which is beveled to afford the usual valve seat. This orifice communicates with an intake or exhaust passage 3, according to the purpose and location of the valve. A guide sleeve 4 is provided in this main 75 structure or mounting. It will be understood that the mounting disclosed is for illustrative purposes only and forms no part of the invention *per se*.

Mounted for reciprocatory movement in 80 the guide sleeve 4 is the valve stem 5 having at its upper end a spherical head 6. The valve stem is actuated by a cam or tappet and retracted by a spring, or other means (neither of which is shown) as is customary 85 in such constructions.

The valve head 7 is of dished or concaved form and is preferably though not necessarily, stamped from sheet metal. It is provided with a centrally disposed spherical 90 socket portion 8 which conforms to the contour of the valve stem head 6. The rim or periphery of the head 7 is inturned or clenched at 9 over the peripheral edge of a concave disk 10. The engagement of the 95 disk 10 and inturned rim 9 of the valve head is sufficiently tight to place the disk under sufficient tension to maintain a normal compression tight engagement of the spherical head 6 of the valve stem within the socket 100 portion 8.

Intermediate the oppositely disposed concave head members 6 and 10 is formed a chamber 11 communicating with the pressure chamber 1 through orifices 12. To afford access to the valve stem head for manufacturing operations, a central opening 13 is provided in the disk 10. For the same purpose a center or counter sink 14 is provided in the head 6. The opening 13 and center 110 14 however are not essential to the operation of the device but are only for convenience of

manufacture. The periphery of the head portion 7 is beveled at 15 to agree with the valve seat.

As thus constructed the valve head is capable of both rotary and tilting movement in relation with the valve stem. The engagement of the head 6 and socket portion 8 affords a ball and socket or universal joint which enables the automatic adjustment of the valve to the seat. The grip of the valve head upon the stem is sufficient to enable it to yieldingly maintain its adjusted position true with the valve seat, to which it is forced by the action of the spring and the drop of the valve upon the seat.

Valves as usually constructed do not completely close or seat true at their first contact with the valve seat. After the initial contact of the valve and seat a lateral shifting movement ordinarily occurs before the valve finds its proper seating location. This is particularly true in the case of worn valve stems and guides. The readjustment or side shift is accomplished under the influence of the retracting spring. The interval of time required for such readjustment is substantially uniform while the time of the valve travel is reduced with increased speed of the engine. This variation in time ratio between the timed movement of the valve and the interval of readjustment, results in failure of the valve to be fully closed during too great a portion of the piston stroke.

The freedom of the valve head, due to the universal joint, permits the valve head to tilt until it assumes a position parallel with the plane of the valve seat and so effects a complete closure at the initial contact without requiring the lateral shifting adjustment.

This freedom of the valve head to tilt upon engagement with an uneven seat further induces a rotary movement of the head about the stem which is normally held against rotation by the retracting spring. The rotary movement is not very great at any one stroke, but by marking the valve head and seat and operating the valve repeatedly upon an uneven seat, the rotary movement will be clearly demonstrated. The degree of movement will be somewhat dependent upon the inequality of the seating contact. If the tilting movement of the valve head was always in a direction coincident with its axis or a true diameter, as the line $a-a$ in Fig. 3, the rotation would be small. However in engaging an uneven seat the tilting is more often in directions off center as indicated by lines $x-x$, $y-y$, and $z-z$ in Fig. 3. This gives to the valve a rolling contact which causes a rotary travel of the valve head upon its seat which is positive and continuous so long

as a lack of uniformity in the seating contact exists. This causes the valve head to wear itself into the seat until a perfect fit is effected. A perfect fit having been thus automatically attained the wearing action will cease unless something occurs to disturb or destroy the contact or fit of the valve head. Thereupon the rotary movement is again established in proportionate degree to compensate for the existing inequality. This effects the automatic removal of carbon deposits from the valve bearing surface and valve seat, and automatically overcomes any warping of either the head or seat.

The disk 10 may be made sufficiently heavy to be rigid and unyielding to the thrust impulse of the valve stem, thereby positively carrying the head 7 in unison with the valve stem and against the pressure within the chamber 1.

However for some purposes and conditions of use, the disk 10 is made slightly resilient or yielding. The yielding of the disk 10 permits the spherical head 6 to be unseated from the socket portion 8 at the initial impulse of the valve stem and so momentarily opens an auxiliary bypass from the chamber 1, through the orifices 12, chamber 11, and between the head 6 and interior of the socket 8 (as indicated by arrows in Fig. 2) so long as the valve head 7 is retarded by pressure in the chamber 1 and the inertia of the member. This slight preliminary release of pressure facilitates the quick action of the valve and minimizes the force necessary to unseat the valve. Further it materially reduces the report or noise of the exhaust upon the complete unseating of the valve.

The resiliency of the disk or diaphragm 10 and the preliminary release of pressure reduces the strain upon the valve actuating cam or tappet and reduces the shock and noise at the reseating of the valve. The flexibility or yielding characteristic of the construction permits the internal pressure to press the valve firmly upon the entire seat, thus insuring against loss of compression.

As usually constructed valve heads vary in thickness and therefore absorb and radiate heat unevenly. This results in a tendency of the valve head to warp or change its shape either temporarily or sometimes permanently. It is to be noted that in the present construction the head members 7 and 10 are of substantially uniform thickness throughout each member. This uniformity of cross section reduces the tendency to warp, which tendency is further obviated by the opposed convexity of the respective members.

The chamber 11 serves as a condensation chamber for oil vapors carried in the ex-

- haust gases. The lower member 7 being less heated collects and condenses these oil vapors which then under influence of gas pressure and capillary attraction enter between 5 the head 6 and socket 8 thus lubricating the universal joint and thence creep along the valve stem to the guide 4.
- The lower section of the head being of less mass than the ordinary solid head, radiates its heat quickly and so preheats by 10 contact the incoming charge of fuel, thereby preventing condensation of the fuel in the intake passage and materially aiding vaporization. This absorption of heat from the head by the fuel charge cools the head to 15 increase condensation of oil vapors of higher temperature.
- From the above description it will be apparent that there is thus provided a device 20 of the character described, possessing the particular features of advantage before enumerated as desirable but which obviously is susceptible of modification in its form, proportion, detail construction or arrangement 25 of parts, without departing from the principle involved or sacrificing any of its advantages.
- While in order to comply with the statute, the invention has been described in 30 language more or less specific as to certain structural features, it is to be understood that the invention is not limited to any specific details, but that the means and construction herein described comprise but one 35 mode of putting the invention into effect, and the invention is therefore claimed broadly in any of its possible forms or modifications within the scope of the appended 40 claims.
- Having thus described my invention, I claim:
1. A puppet valve comprising two concave members peripherally interengaged one with the other to form a valve head and a 45 valve stem having a head thereon clamped between said concave members.
  2. A puppet valve comprising a two part valve head, the periphery of one of said parts being engaged with the periphery of 50 the other part, said parts being centrally separated one from the other to form an intermediate chamber, and a valve stem in relation with which both the head parts are relatively movable.
  3. A puppet valve comprising, a valve 55 head, a resilient disk connected therewith, and a valve stem movable in relation with the valve head against the tension of said disk.
  4. A puppet valve comprising a valve 60 head, a valve stem movable in relation with said head, and a resilient member engaging said head and stem against the tension of which said parts are relatively movable.
  5. A puppet valve comprising a valve 65 head having a seat engaging face thereon, said head member having an opening therein, a valve stem extending through said opening, and resilient means against the tension of which the head and stem are 70 relatively movable.
  6. A puppet valve comprising a valve head having a port therein, a valve stem having a head thereon normally closing said port, and resilient means engaging the head 75 and valve stem against the tension of which the stem is movable independent of the head to open said port.
  7. A puppet valve comprising a chambered valve head, having a normally open 80 port leading to the said chamber from the high pressure side of said valve head, and having a normally closed port from said chamber to the low pressure side of said valve head, and a valve stem relatively mov- 85 able in relation with said valve head adapted by such relative movement to open and close the last mentioned port.
  8. In a valve construction of the character described, a valve stem, a valve head 90 carried thereby comprising two members peripherally interengaged one with the other and centrally separated to form an intermediate chamber one of said members being resilient, and a head upon said valve 95 stem clamped intermediate said members by the resiliency of said resilient member.
  9. In a valve construction of the character described, a valve stem, a valve head 100 comprising two members peripherally en- 105 gaged one with the other and centrally separated to form an intermediate chamber, one of said members being resilient, whereby the valve stem is initially permitted to move against the tension of said member independent of the other member.
  10. In a valve construction of the character described, a valve stem and a valve head comprising two members peripherally 110 interengaged one with the other and centrally separated to form an intermediate chamber, one of said members containing an intercommunicating orifice between said chamber and the high pressure side of said 115 valve.
  11. In a valve construction of the character described, a valve stem, a valve head carried thereby comprising two members peripherally interengaged one with the other, one of said members being resilient, 120 said valve stem being movable against the tension of said resilient member independent of the other member and a bypass opened through the valve head by such movement of the valve stem.
  12. In a valve construction of the character described, a valve stem, a valve head carried thereby comprising two members peripherally interengaged one with the 125 other and centrally separated to form an in-

- termediate chamber, one of said members having an orifice therein leading to said chamber, and a head upon said valve stem normally closing said orifice, the valve stem 5 being movable independent of said member to effect the opening of said orifice.
13. In a valve construction of the character described, a valve stem, a valve head member having an orifice therein, a head 10 upon the valve stem normally closing said orifice and a resilient abutment for said valve stem carried by said valve head member against the tension of which the valve stem is movable independent of the head member to effect the opening of said orifice.
14. In a valve construction of the character described, a valve stem and a relatively movable hollow valve head carried thereby, said valve head having a valved 20 orifice affording a means of communicating between the interior chamber of the hollow valve head and the exterior thereof and controlled by the relative movement of the head and valve stem.
15. A puppet valve comprising a valve head having a port therein, a valve stem therefor having a head thereon normally closing said port, and a yielding abutment 30 for said valve stem which in turn abuts upon said valve head.
16. In a valve construction of the character described, a valve stem, a valve head, a yielding joint connecting the valve head and stem, and means affording yielding resistance to the longitudinal movement of 35 the stem toward said head.
17. In a valve construction of the character described, a valve stem, a disk-like valve head carried thereby capable of a tilting movement independent of the valve stem, 40 and means affording yielding resistance to the tilting movement of the head in relation with the stem.
18. A puppet valve comprising two interengaged head members formed from 45 sheet material, and an independently formed valve stem connected therewith.
19. A puppet valve comprising a head having an orifice therein, and a valve stem, said head and stem being capable of relative movement in relation one with the other whereby the orifice in said head is controlled.

In testimony whereof, I have hereunto set my hand this 31st day of January, A. D. 55 1918.
